Primary Examiner — Kevin K Rudzinski*Assistant Examiner* — Clare Ann Gannon(74) *Attorney, Agent, or Firm* — Thorpe North & Western, LLP(57) **CLAIM**

The ornamental design for a support mat, as shown and described herein.

DESCRIPTION

FIG. 1 is a perspective view of my support mat in accordance with my invention;

FIG. 2 is a top view thereof;

FIG. 3 is a bottom view thereof; and,

FIG. 4 is a left side view thereof, the front, rear and right side views being the same.

The broken lines depict portions of the article that form no part of the claimed design.
